UNITED STATES PATENT OFFICE.

WILLIAM P. TAGGART, OF PHILADELPHIA, PENNSYLVANIA, ASSIGNOR OF ONE-HALF TO THEODORE H. BECHTEL, OF SAME PLACE.

DESIGN FOR A LUMP OF FUEL.

SPECIFICATION forming part of Design No. 24,313, dated May 14, 1895.

Application filed April 4, 1895. Serial No. 544,484. Term of patent 14 years.

To all whom it may concern:

Be it known that I, WILLIAM P. TAGGART, a citizen of the United States, and a resident of the city and county of Philadelphia, State 5 of Pennsylvania, have invented and produced a new and original Design for Lumps of Fuel Made from Coal-Dirt, of which the following is a specification, reference being had to the accompanying drawings, which form part of 10 this specification, and in which—

Figure 1 is a perspective view of a lump of fuel of my design; Fig. 2, a plan of my lump of fuel; Fig. 3, a side elevation of the same; Fig. 4, a section of Fig. 3 on line 1 2, and Fig. 15 5 a section of Fig. 2 on line 3 4.

My lump of fuel has the form shown in the

drawings, that is, it is rectangular in section with rounded corners as shown in Figs. 2 and 4, and its sides or faces A, A' are curved from the base upward as shown in Figs. 1 and 3. 20

A central section through my lump of fuel on the line 3—4, Fig. 2 shows a figure which is bounded substantially by two arcs of circles united at a common chord as shown in Fig. 5.

I claim as my invention—

The design for a lump of fuel as herein set forth.

WILLIAM P. TAGGART. 25
